FIG. 5

FIG. 6

FIG. 7

FIG. 8

FIG. 1 is a perspective view of the lighting fixture showing my new design.

FIG. 2 is an enlarged end elevation thereof as seen from the opposite end of FIG. 1,

FIG. 3 is a top plan view thereof,

FIG. 4 is a side elevation thereof as seen from the opposite side of FIG. 1,

FIG. 5 is an enlarged detail perspective view of the prismatic pattern on the bottom of the lens panel,

FIG. 6 is an enlarged detailed perspective view of the prismatic pattern on the side of the lens panel,

FIG. 7 is an enlarged fragmentary sectional view taken on line 7-7 of FIG. 2, and

FIG. 8 is an enlarged fragmentary sectional view taken on line 8-8 of FIG. 2.

The prismatic pattern on the side and bottom of the lens in FIG. 1 and on the side of the lens in FIG. 4 which is only partially shown, is understood to cover the entire side and bottom surface thereof.

I claim:

The ornamental design for a lighting fixture, substantially as shown and described.
